THOMAS McCABE, OF HOMESTEAD, PENNSYLVANIA.

CRANKING DEVICE.

1,087,800.

Specification of Letters Patent. Patented Feb. 17, 1914.

Application filed September 22, 1911. Serial No. 650,737.

To all whom it may concern:

Be it known that I, THOMAS McCABE, a citizen of the United States, and a resident of Homestead, in the county of Allegheny 5 and State of Pennsylvania, have invented a new and Improved Cranking Device, of which the following is a full, clear, and exact description.

My invention relates generally to cranking devices for use on gas or gasoline engines and the object of my invention is to provide a structure whereby cranking of such engines previous to starting is rendered less dangerous.

15 A further object of my invention is to provide a device of the class described which is especially adapted for use on automobiles and gasoline engines, the construction and arrangement being such that the brakes 20 must be set and the speed change lever must be in neutral position before the cranking can take place, and in the event of a back fire from the engine the crank will immediately disengage from the engine shaft.

25 A further object of my invention is to provide a device of the class described which consists of few parts, thereby making it of low cost, the use of such a device being intended to prevent injury to a person while 30 cranking an explosive engine.

Reference is to be had to the accompanying drawings forming a part of this specification, in which similar characters of reference denote corresponding parts in all the 35 views, and in which—

Figure 1 is a front view, partly in section, on the line 1—1 of Fig. 2; Fig. 2 is a vertical sectional view on the line 2—2 of Fig. 1; Fig. 3 is a sectional view on the line 3—3 40 of Fig. 2; Fig. 4 is a partial side view of the ratchet wheel with the different teeth thereon; Fig. 5 is a rear view of this ratchet wheel; Fig. 6 is a side view, partly in section, showing the means whereby turning of 45 the ratchet wheel is made to depend on the position of the speed change lever; Fig. 7 is a vertical sectional view on the line 7—7 of Fig. 8; Fig. 8 is a vertical sectional view of a modified form of construction; Fig. 9 is 50 a partial top plan view of the ratchet wheel used in this modification.

The cranking device is adapted to be at-

tached to the frame 1 which carries the engine, the standard 2 being secured to the frame by any suitable means such as bolts 3. 55

Extending transversely of the frame 1 and carried by the standard 2 is a suitable bearing 4 through which the crank shaft 5 extends, the outer end being provided with a cranking handle 6.

60 Freely mounted on the standard 2 and concentric with the shaft 5 is a disk 7 having a plurality of peripheral serrations 8, one side of the disk being provided with a number of equally spaced notches 9, the opposite side of the disk being also provided with notches 10. The disk 7 is freely rotatable on its support and is held in position thereon by means of a suitable plate 11 which is maintained in position by means 65 of machine screws or bolts 12; the front of the disk 7 is preferably recessed as at 13 in order to form a pocket into which the plate 11 may fit, thereby providing for a neater and less extended construction.

75 The engine shaft 14 extends closely adjacent the inner end of the crank shaft 5, and the adjacent ends of each of these shafts are provided with co-acting parts forming a clutch, the crank shaft having arms 15 80 thereon, the arms being provided with teeth 16, the shaft 14 being provided with a circular plate 17 having a series of notches 18 into which the teeth 16 are adapted to engage, whereby the engine shaft may be 85 turned; the teeth 19 between the notches 18 are tapered so that the free backward movement of one of the parts relatively to the other is permitted.

On the front of the standard 2 and at opposite points are the pawls 21, 22, pivotally secured thereto by means of bolts 23, 24, the free ends of the pawls being adapted to engage in the serrations 8 on the periphery of the disk 7. Directly above these pawls are 95 lugs or projections marked X; these lugs are cast with the standard 2 and prevent the pawls going back so far that they will not engage with the teeth 8.

Secured to the crank shaft 5 in any suitable manner and turning therewith when the crank handle 6 is turned are the oppositely extending arms 25, 26, the outer ends of which are adapted to be brought into en-

gagement with opposite notches 9 on the front of the disk 7 by pressing inwardly on the crank handle 6 against the tension of a suitable helical spring 27 positioned within 5 a pocket 28; this spring keeps the crank shaft normally in front of the disk 7 and the ends of the arms 25, 26, out of engagement with the notches 9 so that, after the engine is started, the parts of the clutch at 10 the adjacent ends of the engine shaft 14 and the crank shaft 5 are out of engagement with each other, whereby the engine may turn independently of the cranking device; it is to be noted that the teeth on the rear 15 side of the disk 7 are untapered while those on the front side are preferably tapered, as shown particularly in Fig. 4. Hence, the members 15 and 17 which form a clutch are for the purpose of rotating the engine shaft 20 through the medium of the starting crank; when the engine starts the inclined teeth 19 allow the engine shaft to rotate faster than the shaft of the starting device and the inclined surfaces on these teeth throw the 25 shaft outwardly. If the engine back-fires the clutch element 15 and the shaft 5 are carried backward by the clutch element 17; but the ratchet plate or disk 7 is held against movement under such circumstances 30 for the reason that the pawls 21—22 engage with the peripheral teeth of this disk; the inclined teeth 9 on the disk 7 and the ends of the arms 26 on the crank handle are thrown out of engagement, whereby the 35 members 15 and 17 are also disengaged.

My invention is designed principally to prevent cranking of the engine when the brakes are off and when the speed change lever is in any other position than neutral, 40 the construction whereby such a result is obtained being as follows: Extending rearwardly of the disk 7 and mounted in any suitable manner is a rod 30 having a helical spring 31 mounted thereon, the forward 45 end 32 of this rod being adapted to be seated within any one of the notches 10 on the rear face of the disk 7; the rod is movable against the tension of the spring to carry it out of any one of these notches in the following manner: The shaft 33 (see Fig. 6) 50 which has the speed change lever at its outer end is provided with a cam 34 extending transversely from one side thereof, the opposite faces 35, 36, being inclined; the rod 30 is extended backwardly a suitable distance and at its rear end is pivotally supported at 37 to one end of a bell crank 38 mounted in any suitable manner at 39, the other end of this bell crank being provided 55 with a roller 40 which engages either one of the inclined faces 35, 36, of the cam 34 or the horizontal end portion 41 thereof depending on what position the speed change lever may occupy. When the parts are in 60 the position shown in Fig. 6 in full lines

the end 32 of the rod 30 is in engagement in one of the notches 10 on the side of the disk 7, such engagement being also maintained when the speed change lever has been moved to bring the inclined face 35 into engagement with the roller 40; when this lever is in neutral position the horizontal end portion 41 of the cam 34 comes into engagement with the roller 40, thereby turning the bell crank about the point of support 39 and moving the rod 30 so that its vertical end 32 is brought out of engagement with the notch in the disk. In such position the disk is freely rotatable and the engine may be cranked. In order to provide for non-interference with the engine case, the rod 30 may have its intermediate portion offset as at 30' (see Fig. 1) and then extended rearwardly as at 30''. A similar cam may be mounted on the shaft to which the brake lever is attached and another bell crank and movable rod 50 may also be provided, the outer end of this rod being also adapted for engagement in any one of the notches 10 so that the disk 7 cannot be turned save when the brakes are set; such a result is attained by providing that the horizontal end portion of the cam on the brake lever shaft is in position to move the rod 50 out of engagement with the notches 10 when the brakes are set, such being easily obtained by the proper positioning of the cam and the lever. Any portions of this rod 50 may be offset as at 50' (see Fig. 1) in order to clear the crank case and other changes or variations 95 therein may be made in order to provide for easy and safe operation of the parts.

The operation of my device is as follows: With the engine standing still and the brakes on, and the speed change lever occupying a normal position, the disk 7 is freely rotatable on its support; by pushing inwardly on the crank handle 6 the co-acting parts of the clutch adjacent the engine shaft 14 are brought into engagement and the outer ends of the arms 25, 26, engage in the notches 9 on the front of the disk 7 so that by turning the handle the motor is cranked. In the cranking operation the pawls 21, 22, merely slip over each of the peripheral teeth 8 so that these elements, while preventing turning of the disk in an opposite direction to that of cranking, yet do not interfere with turning in a normal direction. After the machine has gotten under way the handle 6 is released, the spring 27 forcing it outwardly and the parts of the clutch adjacent the end of the engine shaft free of each other; such movement also frees the arms 25, 26, of engagement with the teeth on the front of the disk 7. If, however, it is attempted to crank the motor when the brakes are off or when the speed change lever is in any other position than neutral, the end portions of the rods 30 and 50 will engage in 100 105 110 115 120 125 130

the notches 10 on the rear face of the disk 7, thereby preventing turning of this disk and consequent turning of the crank handle and engine shaft when the crank handle has 5 been pushed inwardly. In the event of the engine back-firing, when it is otherwise ready for cranking, the pawls 21, 22, will prevent reverse rotation of the disk 7 and also of the crank handle because of the engagement of the parts, the crank will immediately become disengaged from the engine, thus preventing injury to the operator.

In Figs. 7, 8, and 9, I have shown a modification of the cranking device, the change 15 of construction being as follows. The crank handle 6 in this instance is freely rotatable on the outer end of the engine shaft 14 while the helical spring 27 keeps the disk 7 and the arms 25', 26', out of engagement, the 20 crank handle being removable in this instance if so desired whereby the modified construction is especially adapted for use on marine engines. The disk 7 is freely mounted on its support similar to the construction previously described and is retained in position by the plate 11 in a similar manner. Adjacent the front of this plate and held fast on the engine shaft is a plate or disk 60 having a plurality of notches 61 30 around its periphery, these notches registering with certain of the notches 9 in the front of the disk 7; the rear side of each of the arms 25', 26' is provided with diametrically opposite teeth 62, each of the teeth being 35 adapted to pass through the notches 61 in the plate or disk 60 and come into engagement in opposite notches 9 on the disk 7. The movable rods 30, 50, which are actuated by the brake lever and the speed change 40 lever respectively are maintained in this position, either or both of them being adapted to be seated in the notches 10 on the rear of the disk 7, as previously described. When it is desired to crank the motor the handle 6 is placed on the end of the engine shaft 14 and pushed inwardly against the pressure of the spring 27; the teeth 62 engage the notches 61 and 9, as previously mentioned, and if the rods 30 and 50 are out of engagement with the notches 10 the engine may 45 be cranked; if, however, the speed change lever and the brake lever are in any position save one, the disk 7 cannot be turned, and, hence, the engine cannot be cranked. The 50 disk 7 is provided with the peripheral teeth and the co-acting pawls previously described so that reverse rotation of the handle is prevented in case of back-firing.

From the above description taken in connection with the accompanying drawings it will be seen that I have provided a cranking device having certain characteristics tending toward safety of the operator as set forth in the beginning of this specification.

Of course the size of the various parts

and their relative position with respect to one another can be varied in order to adapt the device to different engines and different uses without departing from the spirit and scope of the invention as defined in the appended claims.

Having thus described my invention, I claim as new, and desire to secure by Letters Patent:

1. In combination with a brake lever, and an engine shaft, a disk freely supported concentric therewith, notches on opposite faces of the disk, a cranking device for engagement with the said shaft and having portions adapted for engagement with the notches on one side of the disk, together with means adapted to be moved into and out of engagement with the notches on the other side of the disk and operable by movement of the brake lever whereby the engine shaft 75 may be turned by the cranking device only when the said brake lever is in a certain position.

2. In combination with a brake lever, and an engine shaft, a disk having notches on opposite faces thereof, a cranking device for engagement with the shaft and having means for engagement with the notches on one face of the disk, other means adapted for engagement with the notches on the other face of the disk and in operative relation with the brake lever, whereby the cranking device is prevented from turning the engine shaft save when the brake lever is in one position.

3. In combination with an engine shaft, a freely rotatable member having notches on one face, a cranking device adapted for engagement with the engine shaft and provided with arms having locking engagement 105 with the said rotatable member when the cranking device is in engagement with the shaft, and means adapted to be brought into or out of engagement in one of the said notches whereby the said member is prevented from turning and the cranking device is held inoperative.

4. In combination with a brake lever, a speed change lever, and an engine shaft, a rotatable member having notches on opposite faces thereof, a cranking device adapted to engage the said shaft and having means thereon adapted to engage the notches on one side of the disk whereby the disk is turned when the engine is cranked, together with means adapted to engage any one of the notches in the other side of the said member and operable by movement of the brake lever or the speed change lever whereby, when either of these said levers is in a certain position the cranking device is held inoperative.

5. In combination with an engine shaft, a rotatable member having notches on opposite faces thereof, a cranking device having 130

- means thereon adapted to engage the engine shaft and other means for engagement with the notches on one side of the said member, there being other means adapted to engage 5 in any one of the notches on the other side of the said rotatable member whereby the cranking device may be held inoperative.
6. In combination with a brake lever, a speed change lever, and an engine shaft, a 10 movable member having notches on opposite sides thereof, a cranking device having means thereon adapted for engagement with the engine shaft, and also provided with other means adapted for engagement with 15 the notches in one side of the said member, rods adapted to engage in the notches on the opposite side of the said member, the said rods being in operative relation with the brake lever and the speed change lever 20 whereby the cranking device may be held inoperative when either of these levers occupies certain positions.
7. In combination with an engine shaft, a movable member having notches on opposite 25 sides thereof, a cranking device having means thereon adapted to engage the engine shaft and having other means adapted for engagement in any one of the notches on one side of the said member, and movable 30 means adapted to be brought into and out of engagement in any one of the notches in the opposite side of the said member whereby the cranking device may be held inoperative.
- 35 8. In combination with an engine shaft, a cranking device comprising a handle, a movable member adjacent the said device, coacting parts carried by the cranking device and the engine shaft, means carried by 40 the cranking device adapted for engagement with the said movable member when the cranking device engages the engine shaft, and movable elements adapted to be brought into engagement with the said movable member whereby, when either of the said elements engages the said member, the said 45 cranking device is held inoperative.
9. In combination with a brake lever, a speed change lever, and an engine shaft, a 50 cranking device comprising a handle, a disk having notches on opposite faces thereof, coacting parts carried by the cranking device and the engine shaft, other means carried by the cranking device adapted for engagement 55 with the notches in one side of the said disk, movable rods, either one of which is adapted to be brought into and out of engagement with any one of the notches in the opposite side of the member, the said rods 60 being provided with means whereby they

may be actuated by the brake lever or the speed change lever whereby, when either of these levers is in a certain position, the cranking device is held inoperative.

10. In combination with a brake lever, 65 a speed change lever, and an engine shaft, a cranking device adapted to be moved into engagement with the shaft in order to turn the same, a movable member adjacent the device, means carried by the device for engagement with one face of the said member when the cranking device is in operative position, and means actuated by movement of the brake lever and speed change lever for engagement with the other face of said member, 70 whereby the said device is held inoperative save when the said levers are in certain positions.

11. In combination with the controlling mechanism of an automobile and an engine 80 shaft, a freely rotatable member, a cranking device adapted for engagement with the engine shaft, and having interlocking engagement with one face of the said member when it is in engagement with the shaft, a member 85 for engagement with the other face of the said member to lock the said member and the cranking device inoperative, and means for operating the member from the controlling mechanism of the automobile. 90

12. In combination with an engine shaft, a freely rotatable member, a cranking device adapted for engagement with the engine shaft and having locking engagement with one face of the said member when it is 95 in engagement with the shaft, a sliding rod adapted to interlock with the said member to hold it and the cranking device inoperative, a speed change lever shaft, and means for operating said rod from said shaft. 100

13. In combination with an engine shaft, a freely rotatable member, a cranking device adapted for engagement with the engine shaft and having locking engagement with the said member when it is in engagement 105 with the shaft, a sliding member for engagement with the revolute member to lock it and the cranking device inoperative, a speed change lever shaft, a cam on the shaft, and a bell crank having one member connected with the sliding member and its other member extending in the path of the cam.

In testimony whereof I have signed my name to this specification in the presence of two subscribing witnesses.

THOMAS McCABE.
